N. F. EGLER

FURNACE

Filed Oct. 16, 1922

Fig. 1.

Fig. 2.

Inventor:
Nicholas Frederick Egler,
By Duly authorized, Chrissie and Willa,
Attest,

UNITED STATES PATENT OFFICE.

NICKOLAS F. EGLER, OF CHICAGO, ILLINOIS.

FURNACE.

Application filed October 18, 1922. Serial No. 594,773.

To all whom it may concern:

Be it known that I, NICKOLAS F. EGLER, a citizen of the United States, residing at Chicago, in the county of Cook and State 5 of Illinois, have invented a new and useful Improvement in Furnaces, of which the following is a specification.

This invention relates to furnaces and is particularly adapted to be used on reversing open-hearth steel furnaces although it will be readily understood that it is equally adapted for use in continuous heating furnaces. The invention is fully described in the following specification and shown in 15 the accompanying drawings in which—

Figure 1 shows a vertical longitudinal cross section of one end of an open hearth furnace embodying the invention, and

Figure 2 is a similar view of a modified 20 form of the invention.

This furnace comprises a hearth 10, a roof 11, and a mixing port 12 which communicates through an air duct 13 which if desired may lead to any well known type 25 of air regenerator.

Extending into the back of the mixing port 12 is a fuel mixing pipe or nozzle 14 which communicates with a source of oil supply through the pipe 15 and with a 30 source of combustible gas supply through the pipe 16. These pipes are preferably under substantially the same pressure and are controlled by the valves 17 and 18 respectively.

35 In operation, air is supplied to the air duct 13 and oil or the like to the pipe 15. Producer gas, coke oven gas, or the like is brought into the mixing nozzle 14 and serves to spray the oil or powdered fuel into the 40 furnace chamber. With the pressure in the two pipes 15 and 16 substantially equal, there is no tendency for the pressure in the nozzle to back up into either pipe and cut off flow therethrough.

45 Heretofore it has been customary to use compressed air or steam for spraying fuel oil into the furnace with the result that when the furnace is not up to the full melting temperature, the air or steam tends to retard ignition and combustion of the oil. As a result some of the unburned products are carried through the furnace and are deposited on the walls of the checkerwork of the regenerator (not shown). This is 50 true even though in some cases fuel gas is

also fed into the chamber along side the fuel oil.

By using fuel gas for spraying or atomizing the fuel oil an intimate mixture of the two is obtained. The gas readily mixes 60 with the air in the port 12, and burns thereby igniting the fuel oil and producing its early combustion in the furnace chamber.

In Fig. 2 is shown a form of nozzle adapted 65 for the use of powdered fuel. In this form powdered fuel is fed through the pipe 19 under a slight pressure to the larger pipe 20 when it is caught by fuel gas under pressure issuing from the pipe 21 and 70 blown into the mixing port 12^a when it mixes with air from the air duct 13^a. It is not desirable to use much pressure on the powdered fuel and hence the outlet 20 must be larger to prevent the higher pressure in 75 the pipe 21 from backing up against the powdered fuel and preventing its passage into the mixing tube 20.

While I have shown and described certain 80 embodiments of my invention, it is to be understood that it is capable of many modifications. Changes therefore, in the construction and arrangement may be made without departing from the spirit and scope 85 of the invention as disclosed in the appended claims, in which it is my intention to claim all novelty inherent in my invention as broadly as possible in view of the prior art.

What I claim as new and desire to secure 90 by Letters Patent is:

1. The process of operating a reversing open hearth furnace consisting of supplying air to the mixing port, supplying liquid fuel under pressure to a point adjacent said mixing port, supplying a combustible gas under pressure to said point, mixing the gas and liquid fuel in a confined space, and spraying and directing the mixture into said mixing port. 95

2. The process of operating a furnace consisting of supplying air to the mixing port, supplying liquid fuel under pressure to a point adjacent said mixing port, supplying a combustible gas under pressure to said point, mixing the gas and liquid fuel in a tube, and spraying and directing the mixture into said mixing port the pressures of the gas and liquid fuel being substantially 105 equal. 110

3. In a furnace, a mixing port, an air duct leading thereto, a nozzle directed into said mixing port, means for supplying combustible oil under pressure to said nozzle, and means for mixing a combustible gas with said oil within said nozzle so that the gas serves to atomize the oil and to direct it into the mixing port, said nozzle being located entirely outside said mixing chamber.
- 10 4. In a furnace, a mixing port, an air duct leading thereto, a nozzle directed into said mixing port and being located outside the same, means for supplying combustible oil under pressure to said nozzle, means for supplying a combustible gas to said nozzle so that the gas serves to atomize the oil, and means for varying the proportions of gas and oil.
- 15 5. In a furnace, a mixing port, an air duct leading thereto, a mixing tube directed toward said port, means for discharging a fuel gas under pressure into said tube, and means for feeding fuel to said tube so that the gas will cause the fuel to be sprayed into said port.
- 20 6. The process of operating a furnace consisting of supplying preheated air to the mixing port, supplying liquid fuel under pressure to a point adjacent said mixing port, supplying a combustible gas under pressure to said point, mixing the gas and liquid fuel in a confined space, and spraying and directing the mixture into said furnace.
- 25 7. In a reversing open hearth furnace, a mixing port, an air duct conducting preheated air thereto, a nozzle directed into said mixing port, means for supplying combustible oil under pressure to said nozzle, and means for mixing a combustible gas with said oil within said nozzle so that the gas serves to atomize the oil and to direct the mixture into the mixing port.
- 30 8. The process of operating a furnace consisting of supplying air to the mixing port, supplying fuel under pressure to a point adjacent said mixing port, supplying a combustible gas under pressure to said point, mixing the gas and fuel in a confined space, and spraying and directing the mixture into said mixing port.
- 35 40 45
